UNITED STATES PATENT OFFICE.

ARTHUR O. LECHNER, OF PITTSBURGH, PENNSYLVANIA.

DESIGN FOR A PIANO-BACK.

45,563.

Specification for Design.

Patented Apr. 7, 1914.

Application filed December 2, 1912. Serial No. 734,635. Term of patent 14 years.

To all whom it may concern:

Be it known that I, ARTHUR O. LECHNER, a citizen of the United States, residing at Pittsburgh, in the county of Allegheny and State of Pennsylvania, have invented a new, original, and ornamental Design for a Piano-Back, of which the following is a specification, reference being had to the accompanying drawing, forming a part thereof.

I claim:

The ornamental design for a piano back as shown.

ARTHUR O. LECHNER.

Witnesses:

HARREY L. LECHNER,
ARCHWORTH MARTIN.
